U. E. TUOMI

COMBINATION TOOL

Filed Sept. 4, 1926

INVENTOR,
Uno E. Tuomi,
BY *John M. Spellman*
ATTORNEY.

UNITED STATES PATENT OFFICE.

UNO E. TUOMI, OF DALLAS, TEXAS.

COMBINATION TOOL.

Continuation of application Serial No. 52,450, filed August 25, 1925. This application filed September 4, 1926. Serial No. 133,650.

This invention relates to new and useful improvements in combination tools and more particularly it refers to a tool in which is combined a square, tri-square, mitre, bevel, 5 level, depth gage, height gage, plumb, protractor, double protractor, dividers, measuring rule, scribe, marking gage and inclinometer. The present invention is a continuation of application for Letters Patent filed

10 August 25, 1925, Serial No. 52,450.

The combination tool is of such size that it may be conveniently carried in a workman's pocket, and is so simple that any one not skilled in carpentry or the allied arts in 15 which it may be used, can utilize the tool to advantage.

The invention also includes other and further features, which, together with the above, will be clearly understood from a perusal 20 of the following detailed description, in connection with the accompanying drawings and wherein:

Figure 1 is a side elevational view of the combination tool.

25 Figure 2 is an edge view, looking towards the left edge in Figure 1 of the drawing.

Figure 3 is a view similar to Figure 2, taken from the edge opposite to that shown in Figure 2.

30 Figure 4 is another side elevational view, and illustrating the position of the tool when used as a divider or compass.

Figure 5 is a longitudinal sectional view, along line 5-5 of Figure 2.

35 Figure 6 is a cross-sectional view taken on line 6-6 of Figure 1.

Figure 7 is a sectional detail view, Figure 8 being a sectional detail view along line 8-8 of Figure 7; and

40 Figure 9 is also a detail sectional view.

Having a more detailed reference to the drawings, wherein similar numerals designate the various parts, 1 denotes a plate or stock, molded of aluminum or similar light 45 metal. The stock has a bevel edge 2 on all inner sides, the edges being extended beyond the main part or body 1 so as to insure a sufficiently wide edge to permit the stock to stand upright more easily. The plate is substantially of square formation, except the edge 3 which forms an angular relation to the right angular edges, indicated generally at 50 4. The edge 3 extends at an obtuse angular relation with one portion of the stock or plate adjacent the corner, the corner 5 being

rounded as shown. The stock 1 is bored inwardly from the edges 4 as indicated at 6 and in the hollows thus formed are placed spirit levels 6^a. Adjacent the levels are apertures 8 to enable the levels to be read.

60 Referring to Figures 3 and 5; a slot 9 is cut in the plate or stock and is extended at right angles and opens into the angular edge 3. This slot is for the purpose of holding a blade 10, which constitutes a ruling element used in connection with the stock 1.

As will be seen, this blade is slotted at 11 and a pin 12 fastened across the slot 9, permitting the blade to be turned at various angles, as indicated in part in Figures 1 65

and 4. The pin 12 includes a nut 13^a which seats within the recess formed by the extended edges 4 and a small lever 12^a locks the blade 10 in adjusted position. The blade 10 is cut half way through its width, 70

as indicated in Figures 4 and 7 and the cut-away portion forms a leg 13, the upper end at 14 being pivoted to the rule portion 10 by a screw 15. This end of the leg is rounded 75

as shown in the drawing to enable it to be moved clear around so that when fully extended it will form as wide an angle as desirable and used as a protractor. The pin 12 can then be tightened to maintain the leg 80

in adjustable position. In Figure 4 the tool is shown in position when used as a compass or divider and when in this position, in order to hold the ruling element or blade 10 in place a pin 16 is provided. This pin is

passed through a small channel in the end of 85 the blade 10, shown in the figure, and when not in use is held in a like channel in the stock 1 as shown in Figure 1. The leg 13

is pointed on one end and both the leg and the ruling element 10 are provided with 90 markings 17 for making proper measurements.

The plate 1 is also provided with markings 18 and 19 to indicate proper measurements for cutting jack and valley rafters as indicated in Figures 2 and 3. The measurements shown are for different angles made when the ruling element is brought to an angular position with these markings and a proper rafter cut is thus made. The angular 95 edge 3 is also provided with markings 3^a for use as a mitre cut of material.

100 The applicant's combination tool can be used like any other spirit level for plumbing purposes, by resting its base on the surface 110

to be plumbed and adjusting the surface until the spirit glass reads plumb, and is efficient as long as the object to be plumbed is not of too great length. For plumbing long objects the tool has a means for extending the length of its base. In the plate or stock are several apertures 20 for making extensions in plumbing. An extension or straight-edged piece of material is fastened 10 to the stock by passing a nail or similar element through the material into the apertures. For example, say the tool is used in plumbing a door which is warped in the center, but in plumb at the top and bottom. 15 If the tool was placed in the center it would show the door out of plumb, but if the tool was properly in alinement with a true extension and placed against the door it would show it in plumb at top and bottom, but 20* warped in the center. The upper hole 20* is large enough to admit of adjustment on the extension.

When used as a protractor, the leg 13 is moved outward free from the slot 9 to its 25 fullest distance from the blade 10. This is done by moving the pin 12 completely to the outer end of the slot 11. On the end 16* of the pin is a projection 21 which is useful as a tightening and releasing element 30 for small screws. To those skilled in any of the arts to which the invention may be applied, various other uses may be made of the tool.

The invention is not to be restricted, however, to the particular construction shown, 35 but may be modified to come within the meaning of the appended claims.

1. In a combination tool of the character described, a plate of substantially square formation, one edge having an angular relation, one corner being rounded; the edges 40 extending beyond the body of the plate,

said plate having a slot along one edge, a two-part blade pivoted in the slot and arranged so as to be moved to varied angles 45 with relation to the plate, said plate and said blade having markings to indicate measurements of material to be cut.

2. In a combination tool of the character described, a plate having a slot along one 50 edge, a blade pivoted in the slot and arranged so as to be moved to varied angles with relation to the plate, said plate including members to indicate correct position of the tool when used as a level; and 55 said blade being in two separable and pivotally connected parts, one of which includes a pointed leg; said leg and its companion part being adapted to be used as a compass and divider.

3. A combination tool comprising a plate of substantially square formation in outline, one edge being angular and including spirit levels set at different positions to indicate 60 varied angles and proper levels openings 65 adjacent the spirit levels for permitting convenient reading of the levels; said plate having a slot along one edge, a ruling element comprising a two-part blade pivotally arranged in the slot, one of said blade parts 70 having one end rounded and pivotally attached to its companion, the rounded end permitting the blades to be swung freely apart at a wide angle, when used as a protractor, divider and compass.

4. A tool of the character described, comprising a plate having a slot along one edge, a two-part blade pivoted in the slot, said blade having a perforation in its free end, and a pin removably mounted in said perforation.

In testimony whereof I affix my signature.

UNO E. TUOMI.
